UNITED STATES PATENT OFFICE.

JOHN McE. AMES, OF DONGAN HILLS, NEW YORK, ASSIGNOR TO AMERICAN CAR AND FOUNDRY COMPANY, OF ST. LOUIS, MISSOURI, A CORPORATION OF NEW JERSEY.

TRUSS-ROD ANCHOR.

1,078,235.

Specification of Letters Patent. Patented Nov. 11, 1913.

Original application filed March 18, 1910, Serial No. 550,243. Divided and this application filed August 26, 1911. Serial No. 646,252.

To all whom it may concern:

Be it known that I, JOHN McE. AMES, residing at Dongan Hills, Richmond county, Staten Island, New York, and being a citizen of the United States, have invented certain new and useful Improvements in Truss-Rod Anchors, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a top plan view of a portion of a car underframe, taken at the bolster, illustrating the invention applied at the juncture of the bolster and center sill. Fig. 2 is an enlarged transverse sectional view through one of the members of the center sill, said section being taken on the plane of line 2—2 of Fig. 1, and illustrating the invention in end elevation. Fig. 3 is a similarly enlarged transverse sectional view through a portion of the bolster illustrating the invention in side elevation, said section being taken on the plane of line 3—3 of Fig. 1. Fig. 4 is a detail perspective view of the truss rod anchor casting. Fig. 5 is a detail perspective view of the end of the truss rod.

The object of the invention is to provide a means of anchoring the ends of the truss rods to the underframe of a car structure in such manner that said rods may be readily removed without the necessity for destroying rivet fastenings and to effect this result in a simple, substantial and practical manner.

A further object is to provide a truss rod anchor which will serve as a means of strengthening the connection between the center sill and the bolster.

It is not desired to limit this invention to use in connection with any specific form of center sill or transverse members as it is equally applicable to a variety of constructions embodying center sills comprising either a pair of beams or a single beam.

My co-pending applications Serial Nos.

550,243 and 646,252 illustrate an underframe with this invention applied and this is a division of said former application.

In the drawings the invention is illustrated as being employed in connection with a pair of center sill beams and as comprising a pair of independently formed castings attached to the outer faces of the center sill members but it is within the scope of the invention to employ a single casting fixed between the sill members if desired. Obviously the casting or castings are duplicated at each of the bolsters or truss rod ends, and said castings, and their method of attachment being identical, only one need be described in detail, which, referring to the structure illustrated, is as follows: A substantially vertical wall 1 is fixed to one of the side faces of the center sill member 2. A laterally projecting flange 3 is formed upon one side of said wall and laps the upper surface of said center sill and is fixed thereto in any suitable manner. An outstanding vertical wall 4 is formed at the forward end of the wall 1 and said wall 4 is formed at its outer edge with a wall 5 extending substantially parallel with the wall 1 and being spaced from and lapping said wall 1 for forming an opening adapted for the reception of the end of the truss rod. The wall 5 is tapered downwardly to the lower edge of the wall 4 for exposing parts of the wall 1 and facilitating the fastening of said wall 1 to the center sill. In the construction illustrated the bolster comprises a pair of flanged diaphragms as 6—6, disposed with their upper flanges 7—7 in the same plane as the upper faces of the center sill members, and a cover plate 8 extending across the center sill and being fixed to the flanges 7—7. The upper portion of the forward face of the wall 4 abuts the rear edge of the cover plate 8 and is extended above said cover plate and is bent horizontally forward as at 9 and is fixed to the upper surface of said plate. The flange 3 is extended above the cover plate 8 and is likewise fixed to the upper surface thereof as by rivets 10, at least one of which rivets extend through the upper flange 7 of the adjacent bolster diaphragm. The extended portion of the flange 3 and the portion 9 of the wall 4 are substantially continuous and, being integral with the walls 1 and 5,

form a positive and rigid connecting gusset between the center sill and the bolster. The wall 4 may be fixed to the bolster parts when the invention is used in connection with a bolster structure presenting appropriate surfaces. The wall 1 is extended above the horizontal plane of the flange 3 and extends outwardly and forms a top wall as 11 for part of the length of the wall 1, said 10 top wall merging into the upper edge of the wall 5 for strengthening the wall 5 and partly covering the space between the walls 1 and 5. The upper portion of the wall 1 is projected forwardly and forms a strengthening rib for the forward portion of the flange 3 and portion 9 of the wall 4. The inner opposing surfaces of the walls 1 and 5, in that part not covered by the wall 11, are formed with oppositely disposed inclined pockets 12—12, adapted to receive a locking-pin 13, projecting through a suitable eye 14 formed in the enlarged end 15 of the truss rod 16. The pockets 12—12 open upwardly and incline toward the end 25 of the car and the space between the walls 1 and 5 is of sufficient size for allowing the end of the truss rod to be thrust therethrough for enabling the introduction of the pin 13. When the rod is moved into position 30 with the projecting ends of the pin 13 resting in the bottom of the pockets 12, and the car is ready for service, the inability of the rod to have any appreciable longitudinal relative movement will insure against loss of the pin, the pin being held against lateral play by contact of its ends with the walls 1 and 5.

What I claim is:—

1. In an underframe, the combination with 40 a center sill and a transverse supporting member, of a cover plate for said supporting member extending across said center sill, flanged truss rod anchor castings riveted through angularly disposed flanges to said 45 cover plate and directly to said center sill, and truss rods supported in said truss rod anchor castings.

2. In an underframe, the combination with 50 a center sill and a bolster, of a cover plate for said bolster extending across said center sill, flanged truss rod anchor castings lapping and connected to said cover plate and directly to said center sill, and truss rods supported in said seats and removable without 55 destructive effort.

3. In an underframe, the combination with 60 a longitudinal sill and a bolster, of means connecting said sill and bolster, said connecting means being formed with a flanged extension provided with an open pocket forming a truss rod seat, and a truss rod held in said seat and removable therefrom without destructive effort.

4. In an underframe, the combination with 65 a longitudinal sill and a bolster, of a con-

necting casting therefor provided with open pockets at one side of said sill and a truss rod having an enlarged head, a pin disposed in and extending through said head, said pin seated in said pockets and freely removable therefrom without destructive effort. 70

5. In an underframe, the combination with 75 flanged longitudinal sills and a transverse supporting member, of a flanged casting overlapping and connecting said sill and member, said connecting means being formed with an open pocket forming a truss rod seat, and a removable truss rod held in said seat by tension on said rod. 80

6. In an underframe, the combination with 85 flanged longitudinal sills and a transverse supporting member, of flanged castings formed with truss rod pockets supported on the said sills and on said member, and truss rods removably held in said pockets. 90

7. In an underframe, the combination with 95 flanged supporting sills and a bolster, of vertically flanged truss rod supports fixed directly to each and having relatively inclined pockets and a truss rod engaging in said pockets and removable from said pockets without destructive effort. 100

8. In an underframe for cars, the combination comprising a longitudinal sill, a 95 bolster, and a truss rod anchor casting directly connected to the web of said sill and lapping the bolster and provided with an offset portion including an open pocket for a truss rod. 100

9. In an underframe for cars, the combination comprising a longitudinal sill, a bolster, and a truss rod anchor casting directly 105 connecting said sill and bolster and provided with flanges lapping a vertical face and a horizontal face of said sill and having an open pocket for a truss rod which truss rod terminates short of said bolster. 110

10. In an underframe for cars, the combination comprising a longitudinal sill, a bolster, and a truss rod anchor casting directly 110 connecting said sill and bolster and provided with a vertical portion and a horizontal portion lapping said sill and said horizontal portion also lapping said bolster. 115

11. In an underframe for cars, the combination comprising a longitudinal sill, a bolster, and a flanged truss rod anchor casting directly connected to the web of said sill and lapping the bolster and provided with open 120 pockets adapted to receive and retain enlarged end portions of truss rods.

12. In an underframe for cars, the combination comprising a longitudinal sill, a bolster, and a truss rod anchor casting directly 125 connecting said sill and bolster and provided with a vertical portion connected directly to the web of said sill and with a horizontal portion connected directly to said bolster.

13. In an underframe for cars, the com- 130

- bination comprising a longitudinal sill, a bolster, and a truss rod anchor casting directly connecting said sill and bolster and provided with a vertical portion connected 5 directly to the web of said sill and with a horizontal portion connected directly to said bolster, there being open pockets in said anchor casting adapted to receive enlarged end portions of truss rods.
- 10 14. In an underframe, the combination with flanged longitudinal sills and a transverse supporting member, of flanged castings formed with truss rod pockets supported on the said sills and on said member, 15 and truss rods removably held in said pockets.
- 15 15. In an underframe, the combination with a longitudinal sill and a bolster, of a flanged casting connecting said sill and bolster, said casting being formed with an open pocket forming a truss rod seat, and a truss rod formed to be held in said seat by tension on said rod.
- 20 16. In a car underframe, the combination of a center sill including a vertically disposed member, a cross-bearer including a horizontally disposed member, a single casting having flanges contacting with and fastened to said members, and a tension member secured to said casting.
- 25 17. In a car underframe, the combination of a center sill including a vertically disposed member, a cross-bearer including a horizontally disposed member, a single casting having flanges contacting with and fastened to said members, and a tension member removably secured to said casting.
- 30 18. In a car underframe, the combination of a center sill including a vertically disposed member, a cross-bearer including a horizontally disposed member, a single casting having flanges contacting with and fastened to said members, a pocket disposed above said members and a tension member secured in said pocket.
- 35 19. In a car underframe, the combination of a center sill comprising a vertical and horizontal member, a cross-bearer including a horizontal member disposed substantially in a plane with the horizontal member of 40 said center sill and a single casting having flanges fastened to the horizontal and vertical members of said center sill and the horizontal member of said cross-bearer, said casting having means for retaining the end 45 of a tension member.
- 40 20. In a car underframe construction, comprising a trussed center sill and a cross-bearer, means for fastening the tension member to the compression member and cross-bearer, said means comprising a member having an opening extending therethrough, in which opening is adapted to be disposed 45 one end of the tension member.
- 45 21. In a car underframe construction,
- comprising a trussed center sill and a cross-bearer, means for fastening the tension member to the compression member and cross-bearer, said means comprising a member having an opening extending therethrough, 50 in which opening is adapted to be disposed one end of the tension member, and means retaining said tension member removably in place.
- 55 22. In a car underframe construction, a trussed center sill comprising a compression member and a tension member, said tension member having a locking pin extending transversely thereof and a member having a pocket therein carried by the compression member and adapted to contain said pin to removably hold said tension member relative to said compression member.
- 60 23. In a car underframe construction, the combination of flanged center sills and flanged cross-bearers, a single flanged casting fitted between the center sill and cross-bearer, said casting having flanges fitting the flanges of said center sill and cross-bearer, and means passing through contiguous flanges and fastening said casting in place.
- 65 24. In a car underframe construction, the combination of flanged center sills and flanged cross-bearers, a single flanged casting fitted between the center sill and cross-bearer, said casting having flanges fitting the flanges of said center sill and cross-bearer, means passing through contiguous flanges fastening said casting in place, and 70 reinforcing ribs integral with the flanges on the casting and reinforcing the same.
- 70 25. In a car underframe, a bolster comprising vertically disposed diaphragms, and a trussed center sill construction in which the ends of the truss tension members are anchored to a casting connected directly to 75 said sills and with said bolster diaphragms.
- 75 26. In a car underframe, a bolster comprising vertically disposed diaphragms, and a trussed center sill construction in which the ends of the truss tension members are removably seated in a casting connected directly to said sills and with said bolster diaphragms.
- 80 27. In a car underframe, a bolster and a trussed center sill construction, in which the ends of the truss tension members rest in 85 pockets formed in castings secured to said bolster and to vertical parts of said sills.
- 85 28. In a car underframe, bolsters, spaced center sills extending therein, anchor castings connected directly to the webs of said sills and lapping said bolsters and truss tension members having end portions suitably formed to abut against shoulders formed in 90 said castings.
- 90 29. In a car underframe, bolsters, spaced center sills extending therein, anchor castings connected directly to the webs of said 95 sills.

sills and lapping said bolsters and truss tension members having end portions suitably formed to rest in pockets formed in said castings.

5. 30. In a car underframe, bolsters, spaced center sills extending therein, anchor castings connected directly to the webs of said sills and lapping said bolsters below the top plane of said bolsters and truss tension members having end portions suitably formed to abut against shoulders formed in said castings.

10. 31. In a car underframe, a trussed center sill construction in which the ends of the 15 truss tension members are anchored in castings having angularly disposed depending flanges connected with the center sill and a bolster.

20. 32. In a car underframe, a trussed center sill construction in which the ends of the truss tension members rest in open mouthed pockets or grooves formed in a connector between said sill and a transverse member of the underframe, whereby the tension member 25 may be removed without destructive action.

30. 33. In an underframe, the combination with a center sill and a bolster extending across the same, of an anchor plate, disposed at the juncture of the sill and bolster, and comprising a web mounted on the sill, flanges depending from said web and facing the sill and bolster, spaced walls upstanding from said web and formed with pockets, a 35 truss rod having an eye extending between said walls, and a pin extending through said eye and having its ends extending into said pockets.

40. 34. An anchor plate for a truss rod, comprising a web adapted to be mounted upon a center sill and bolster, flanges depending from said web in position for facing the sill

and bolster, and spaced walls carried by said web and adapted to have the end of a truss rod extend therebetween, each of said walls 45 having a pin receiving pocket opening into the space between the walls.

5. 35. In an underframe, the combination with a center sill and a bolster, of truss rod anchor castings secured directly to said center sill, said anchor castings having open mouthed pockets formed therein and truss rods having enlarged end portions seated in said pockets and held therein by tension on said rods, said rods being removable without 50 destructive effort.

36. In an underframe, the combination with flanged longitudinal sills, and a transverse supporting member, of castings having upwardly open truss rod pockets riveted to 55 the webs of said sills and lapping and being secured to said transverse member and truss rods removably held in said pockets.

37. In an underframe for cars, the combination comprising a longitudinal sill, a bolster, and a truss rod anchor casting directly connecting said sill and bolster and provided with a vertical portion and a horizontal portion lapping said sill and said horizontal portion also lapping said bolster. 60

38. In a car underframe, center sills, bolsters, and flanged truss rod anchor castings connected to the webs of said sills between the bolsters and to the bolsters, said anchor castings having upwardly opening pockets 65 adapted to receive enlarged ends of truss rods, and truss rods removably seated in said pockets.

In witness whereof I have hereunto set my hand in the presence of two witnesses.

JOHN MC E. AMES.
